UNITED STATES PATENT OFFICE.

FREDERICK CLARK GRISWOLD, OF PORT JEFFERSON, NEW YORK, ASSIGNOR TO OLIVE A. GRISWOLD, OF PORT JEFFERSON, NEW YORK.

FILM SPLICER.

1,413,269.

Specification of Letters Patent. Patented Apr. 18, 1922.

Application filed September 10, 1920. Serial No. 409,319.

To all whom it may concern:

Be it known that I, FREDERICK CLARK GRISWOLD, a citizen of the United States, and resident of Port Jefferson, in the county of 5 Suffolk and State of New York, have invented a new and useful Improvement in Film Splicers, of which the following is a specification.

This invention provides certain improvements in film splicing machines whereby the film sections may be easily and rapidly prepared for splicing and spliced without shifting the film sections lengthwise, means being employed to so trim the ends of the film 15 sections as to leave overlapping matched portions.

In the accompanying drawings:

Fig. 1 represents a plan view of the machine with one of the film clamps lowered. 20 and the other one raised.

Fig. 2 represents a section on line II—II of Fig. 1.

Fig. 3 represents a section on line III—III of Fig. 1, with the further film clamp lowered. 25

Fig. 4 represents the machine in perspective with the parts in the positions shown in Fig. 1, after the projecting end of one of the film sections has been trimmed by the 30 knife on the film clamp which is shown raised.

Fig. 5 represents an enlarged longitudinal vertical section taken on line V—V of Fig. 1, with both film clamps lowered for splicing the overlapping ends of two film sections. 35

Fig. 6 represents a transverse section taken on line VI—VI of Fig. 5, with the upper jaw of the further clamp member raised and 40 the lower jaw lowered.

Fig. 7 represents the trimmed end of one film section in bottom plan with the cement applied thereto, and the trimmed end of the adjacent film section in top plan with the 45 emulsion removed therefrom.

Fig. 8 represents a top plan view of both film sections after the overlapping ends have been brought together.

The base of the machine is denoted by 1. 50 Lugs 2, 3, 4, 5 uprise from the base at the back thereof, which lugs form supports for a bar 6.

A double shear block 7 is seated at its rear end between the lugs 3 and 4 and at its front 55 end between the lugs 8 and 9. This shear

block has a flat horizontal top face. Between the lugs 3 and 4 is hinged a presser bar 10 having a yielding flat face 11 arranged to be brought into engagement with the top face of the shear block 7 when the 60 presser bar is lowered. A latch bar 12 is hinged to the front of the base 1 in position to engage the free end of the presser bar 10 when the presser bar is lowered between the lugs 8 and 9 which act as guides for the bar. 65 The shape of the hook 13 of the latch bar is such as to exert a cam-like action on the free end of the presser bar to force it into snug engagement with the shear block. In the present instance, this latch bar is mounted 70 on a bar 14 supported in lugs 15, 16; the collars 17, 18 being interposed between the latch bar and lugs. The latch bar has a slight yielding movement with the bar 14 to permit the latch bar to give sufficiently to adapt it 75 to films of varying thicknesses. The film clamps are hinged on the bar 6, one on each side of the presser bar 10, between the lugs 2, 3, and 4, 5, respectively. Adjustable stops 19, 20 are pivoted on the base in position to 80 support the clamps in their lowered position with the top faces of their lower jaws 21, 22 flush with the top face of the shear block 7. Adjustable stops 23, 24 are located on the base at the back thereof in position to engage the upper jaws 25, 26 respectively of 85 the film clamps.

The presser bar 10 has a lost motion connection with the upper jaw 26 of the clamp 22, which lost motion connection is herein 90 shown as provided for by a pin 27 and a slot 28.

The lower jaws 21, 22 of the film clamps are provided with suitable handles 29, 30, respectively, and the upper jaws 25, 26 are 95 provided with suitable handles 31, 32 respectively. The handles 31, 32 are provided with spring catches 33, 34, which serve the double function of locking the two jaws of each clamp together and of locking the 100 clamps to their respective adjustable stops 19 and 20. The lower jaws 21, 22 of the clamps are respectively provided with shear plates 35, 36, which are arranged to coact with their adjacent edges of the shear block 105 7 for trimming off the rough projecting ends of adjacent film sections to be united, as will hereinafter more fully appear.

The lower jaws of the clamps are channeled along their upper faces to provide 110

guides for the film sections and the lower jaws are provided with registering pins 37, 38 for engaging the perforations along that side of the film sections. The upper jaws 5 25, 26 of the clamps have holes for receiving these registering pins when the jaws are closed.

A combined spring guard and guide 39 is secured to the upper jaw 25 of one of the 10 clamps, which guard and guide is provided with a downwardly turned lip 40 arranged to bear against the film section a distance back from its cut edge. This guard and guide serves two purposes; first, to limit the 15 distance back that the emulsion is to be scraped off from the film section, and second, to prevent the spreading of the cement along the film section beyond the overlapping ends of the film sections.

20 Lighting means, such for instance, as an electric lamp 41 is mounted in the base of the machine beneath the shear block and clamps. This light will materially assist in the proper matching up of the film sections 25 and also in manipulating the same.

In splicing the film sections together, several cycles of operations may be employed. For instance, presuming the film sections are to be spliced with the emulsion side upper- 30 most, the cycle of operations may be as follows:

The film clamp 21, 25 may be swung back out of the way. The upper jaw 26, of the other clamp, together with the presser bar 35 10 is raised and the film section is placed in the lower jaw 22 with its end projecting beyond the shear block 7 sufficiently to bring the cross line of one of the picture divisions over the top face of the shear block. The 40 upper jaw 26 and presser bar 10 are then lowered. The film clamp 21, 25 is then swung downwardly, thus causing its cutter plate 35 to shear off the portion of the film which projects beyond the shear block. The 45 film clamp 22, 26 is then raised as is also the upper jaw 25 of the other clamp. The other film section is then placed in the lower jaw 21 with its end projecting beyond the shear block 7 and with the cross line of one 50 of the picture divisions located on the top face of the shear block. The upper jaw 25 is then closed. The clamp 22, 26 is then lowered, causing its cutter plate 36 to coact with the shear block 7 to trim off the portion 55 of the film projecting beyond the shear block. This will leave the ends of the two film sections overlapping on the top face of the shear block. The clamp 22, 26 may then be swung back, together with the presser bar 60 10. The emulsion may then be removed from the top surface of the projecting end of the film section held by the clamp 21, 25, the combined spring guard and guide 39 serving to prevent the emulsion being re- 65 moved too far back from the end. The

cement may then be applied to the exposed surface of the lowered film section, the combined guard and guide preventing the cement from spreading too far back from the end. The film clamp 22, 26, together 70 with the presser bar may then be lowered, bringing the exposed portion of this film section onto the exposed portion of the film section held by the clamp 21, 25. The free end of the presser bar 10 may then be engaged by the cam latch 12 to force the yielding face of the presser bar snugly into engagement with the overlapped ends of the two film sections. The parts may be maintained in this position sufficiently long to 80 permit the ends to be firmly united, after which the upper jaws of the two clamps, together with the presser bar 10 may be thrown back to permit the removal of the united film sections. 85

The spring catches 33, 34 will not lift the lower jaws when the upper jaws and presser bar 10 are raised, the lower jaws, together with the mended film sections remaining in their lowered position. When it is desired 90 to raise the lower jaws either by themselves or with their upper jaws, the handles of the lower jaws may be used.

The function of the yielding face of the presser bar is to ensure an even pressure 95 along the overlapping ends of the film sections even should they vary in thickness.

While the operation of the machine has been described in connection with uniting severed ends of two film sections, it is obvious 100 that it might as well be employed for cutting out a portion of a film and joining the remaining portions or it might be used for joining the ends of two different films.

It will be seen from the above description 105 that the film sections are controlled absolutely from the beginning of the cycle of operations without any tendency of the film sections to shift.

It will also be seen that the matching up 110 of the film sections can be done very rapidly and that after the two ends have been trimmed, they are already overlapped, thus obviating the necessity of shifting the film sections endwise before they are united. 115

It will also be seen that one or both of the film clamps may be swung into and out of engagement with the shear block as desired, thus permitting ready preparation of the film sections for splicing without the necessity of rolling back one or both ends for treatment.

It will be noted that the cutter blades are carried by the film clamps themselves rather than by a separate operative device, the 125 shear block serving both to coact with the shear blades and also with the presser bar in the cycle of operations.

It is evident that various changes may be resorted to in the construction, form and ar- 130

angement of the several parts without departing from the spirit and scope of my invention; hence I do not wish to be limited to the details herein shown and described, but

5 What I claim is:

1. In a film splicer, a shear block, a film carrying clamp arranged to move the film into and out of engagement with the block, means carried by the clamp arranged to coact with the shear block for trimming the end of the film, and a combined guard and guide carried by said clamp. 10
2. In a film splicer, a double shear block, a pair of film carrying clamps located on opposite sides of the block, each clamp being arranged to move a film section into and out of engagement with the block, means carried by the clamp arranged to coact with the shear block for trimming the ends of the film sections, and a combined guard and guide carried by one of the clamps. 15
3. In a film splicer, a shear block, a film clamp comprising upper and lower jaws, a stop, and a common means for locking the jaws together and to the stop. 20
4. In a film splicer, a shear block, a film clamp comprising upper and lower jaws, a stop, and means carried by the upper jaw for locking the jaws together and to the stop. 25
5. In a film splicer, a double shear block, a pair of film carrying clamps located on opposite sides of the block, each clamp comprising upper and lower jaws, stops for the clamps, and a common means for locking the jaws of each clamp together and to its stop. 30
6. In a film splicer, a double shear block, 35
7. In a film splicer, a double shear block, film clamps on opposite sides of the block having cutting edges for trimming the ends of the film sections held by the clamps, and a presser bar having a lost motion connection with one of the clamps for pressing the overlapping ends of the film sections together on the shear block. 40
8. In a film splicer, a double shear block, film clamps on opposite sides of the block having cutting edges for trimming the ends of the film sections held by the clamps, each clamp comprising upper and lower jaws, and a presser bar having a lost motion connection with the upper jaw of one of the clamps for pressing the overlapping ends of the film sections together on the shear block. 45
9. In a film splicer, a double shear block, film clamps on opposite sides of the block having cutting edges for trimming the ends of the film sections held by the clamps, each clamp comprising upper and lower jaws, a presser bar having a lost motion connection with the upper jaw of one of the clamps for pressing the overlapping ends of the film sections together on the shear block, and a combined guard and guide carried by the upper jaw of the other clamp. 50

In testimony, that I claim the foregoing as my invention, I have signed my name, this eighth day of September, 1920.

FREDERICK CLARK GRISWOLD.
